UNITED STATES PATENT OFFICE.

ENGEBRIGHT A. WINDEN, OF WILLMAR, MINNESOTA.

MANIFOLD HOLDER.

Application filed March 4, 1926. Serial No. 92,170.

My invention relates to manifold holders and has for its object to provide a holder which may be readily attached to the manifold studs of an internal-combustion engine 5 so as to clamp either the exhaust or the intake manifold in place while the other of said manifolds is being removed from or attached to the engine.

Another object of the invention resides in 10 providing a reversible holder which is formed on one side with bearing members adapted to engage the intake manifold and on its other side with similar means adapted to engage the exhaust manifold, which 15 holder may be attached in either of its positions to the manifold studs of the engine to clamp either the exhaust or intake manifolds in place.

A still further object resides in constructing 20 said holder from a bar of metal which may be bent to provide two spaced attaching reaches joined by an offset portion issuing outwardly at one side thereof and having legs at their extreme ends extending outwardly in direction opposite to that of said offset portion.

A still further object of the invention resides in forming said attaching reaches 25 with openings for the reception of threaded nuts adapted to pass therethrough which nuts are formed with shoulders positioned nearer one end thereof than the other for engagement with said reaches to permit of attachment of the device to manifold studs 35 of different lengths.

With the foregoing and other objects in view, which will appear in the following description, the invention resides in the novel combination and arrangement of parts and 40 in the details of construction hereinafter described and claimed.

In the drawings illustrating my invention in one form:

Fig. 1 is a perspective view of a holder 45 embodying my invention.

Fig. 2 is an elevational view of a portion 50 of an internal combustion engine showing the exhaust and intake manifolds thereof and illustrating said holder applied thereto for the purpose of clamping the exhaust manifold in place thereon.

Fig. 3 is a sectional view taken on line 3—3 of Fig. 2.

Fig. 4 is a sectional view similar to Fig. 55 3 with the holder reversed and clamping the intake manifold in place.

Fig. 5 is a fragmentary sectional view illustrating the holder attached to relatively long manifold studs.

Fig. 6 is a view similar to Fig. 5 illustrating the application of the invention to relatively short manifold studs.

In the assembly of the intake and exhaust manifolds of the ordinary internal-combustion engine, considerable difficulty and inconvenience is encountered due to the fact that there are six or more two-piece gaskets which have to be properly positioned and held in place while the manifolds are being clamped in place by the usual stirrups on the manifold studs. My invention overcomes this difficulty and greatly simplifies the assembling and removing of manifolds by providing a holding device which may be used to clamp either of the manifolds in place while the other one is being assembled or removed. By thus clamping either of the manifolds in place, and with the other manifold assembled, both of the manifolds may be easily secured in position by the usual retaining stirrups.

For the purpose of illustrating the application of my invention, I have shown in the drawings a portion of the cylinder block 11 of an internal-combustion engine A. This engine is of the ordinary four-cycle type being provided with four exhaust ports 12, 13, 14 and 15 and two intake ports 16 and 17. Exhaust manifold 18 is of usual construction and is formed with conduits 19, 20, 21 and 22 respectively communicating with the exhaust ports 12, 13, 14 and 15.

In addition, an intake manifold 23 is shown which is similarly arranged with two conduits 24 and 25 communicating with the intake ports 16 and 17. In the type of engine illustrated all of the ports 12, 13, 14, 15, 16 and 17 are in alignment and the manifolds 18 and 23 are arranged with faced seats 26, 27, 28, 29, 30 and 31 which extend outwardly from the portions thereof forming the conduits 24, 25, 19, 20, 21 and 22.

Between the conduits 19 and 24 is situated an outwardly extending manifold stud 32 which is anchored to the cylinder block 11 of the engine. Similarly, between the conduits 24 and 20, the conduits 21 and 25, and the conduits 25 and 22, are situated manifold studs 33, 34 and 35 which are in alignment with the exhaust and intake ports previously referred to and with the bolt 32.

When the manifolds 18 and 23 are assem-

bled the same are held in place by means of a number of stirrups such as illustrated at 36 and 37, a stirrup being mounted on each of the stud bolts 32, 33, 34 and 35 and held in place thereon by means of nuts 57. Between the various conduits of the manifolds 18 and 23 and the cylinder block 11 are interposed gaskets 38 such as illustrated in Fig. 3. This construction being 10 well known in the art forms no feature of the invention.

The invention proper consists of a holder indicated in its entirety at B which may be mounted upon and attached to the engine by means of the two manifold studs 33 and 34. This holder is preferably constructed of a bar of metal which may be bent in the form illustrated in Fig. 1. This formed bar includes a central tie or base portion 39, bent 15 along lines 40 and 41 to provide bearing leg-members 42 and 43 turned from said portion 39, body portions or reaches 46 and 47 constituting attaching members oppositely turned into parallelism with the base portion 25 39 on lines 44 and 45, and legs 50 and 51 at the extreme ends of reaches 46 and 47, said legs being bent on lines 48 and 49. With the device so formed it will be noted 30 that the legs 50 and 51 are substantially the same length as the legs 42 and 43 and that said legs 50 and 51 extend from the reaches 46 and 47 on one side thereof while the tie or base portion 39 between the legs 42 and 43 is disposed on the other side of said reaches.

For the purpose of attaching the holder to the manifold studs 32 and 34 of the engine the reaches 46 and 47 are formed with medial slots 52 and 53. These slots are so 40 positioned that the holder may be attached to the engine with the manifold studs 33 and 34 extending therethrough a sufficient distance for the reception of nuts by means of which the holder may be clamped in place. When the holder is used in conjunction 45 with internal combustion engines having sufficiently long manifold studs, the ordinary nuts used for holding the stirrups 36 and 37 in place may be used for clamping the holder in its holding position. When, 50 however, the manifold studs are not sufficiently long, I use a special type of nut soon to be described.

My improved holder is used as follows: 55 As previously brought out, the holder may be used either in assembling or disassembling the manifolds of the engine and for the purpose of illustration, it may be assumed that it is desired to assemble both manifolds upon 60 the engine utilizing my invention for this purpose. The procedure in such case is as follows: The four gaskets 39 belonging to the exhaust manifold 18, are first properly positioned and the exhaust manifold then 65 placed over the same with the conduits 19,

20, 21 and 22 registering with the ports 12, 13, 14 and 15, and with the gasket seats formed thereon properly seated against the respective gaskets. Holder B is next slipped over the manifold studs 33 and 34 with the 70 tie portion 39 next to the exhaust manifold. Said tie portion 39 is of such a length that the ends 54 and 55 of the legs 42 and 43 at their junctions with said tie portion rest upon the seats 28 and 29 of manifold 18. Due to the fact that the manifold 23 is removed from the engine, access may be had to the various gaskets of the exhaust manifold 18 so as to permit of adjusting the same and of temporarily holding them in place when 80 the holder B is clamped down by means of nuts upon the ends of manifold studs 33 and 34. When the holder B is arranged for holding manifold 18 in place, it will be noted that the body reaches 46 and 47 extend a 85 considerable distance outwardly from manifold 18 and that the legs 50 and 51 become even more remotely positioned from said manifold. This permits of readily assembling the manifold 23 and in properly mounting the same with its gaskets so that the conduits 24 and 25 thereof register with the intake ports 16 and 17. After this manifold has been properly mounted, stirrup 36 is placed over the stud bolt 35 and one of the nuts 57 screwed upon the same securely 90 clamps the two adjacent ends of both of the manifolds in place. The other ends of the two manifolds may next be similarly clamped in place by means of the stirrup 37 which is mounted on the manifold stud 32 and engages the seats 26 and 27 of manifolds 18 and 23 and which is held in place 95 thereon by means of the nut 57. The holder B may now be removed and the other two stirrups attached which engage the seats 27, 28, 29 and 30 and hold the manifolds seated and attached in the usual manner. It can thus readily be seen that the manifolds can be assembled individually and in this way 100 conveniently and quickly attached to the engine. If desired the order may be reversed and the intake manifold first assembled and attached. When this is the procedure, 105 holder B is reversed and mounted with the two legs 50 and 51 extending inwardly, said legs engaging the seats 27 and 30 of said manifold and holding the same in place when the nuts are screwed upon the ends 110 of the manifold studs 33 and 34. This allows the exhaust manifold to be next attached and both manifolds clamped in place 115 the same as when the exhaust manifold is first assembled.

My improved manifold holder may be 120 equally well utilized in the removal of the manifolds from the engine. Whenever it becomes necessary to remove one of the manifolds only, as where a new carburetor is 125 installed or the old one repaired, or where 130

a heater is installed or repairs made to the muffler or other devices associated with the exhaust manifold the invention may be used advantageously. In such cases the two inner stirrups are first removed and the holder mounted upon the two manifold studs 33 and 34 to engage the particular manifold which it is desired to hold in place upon the engine. Upon removal of the outer stirrups 10 36 and 37 the desired manifold may be loosened and removed from the engine without interfering with the manifold held in place by means of holder B.

Where the holder is used in conjunction 15 with manifold studs of such length that the same normally project through the openings 52 and 53, the nuts 57 ordinarily used for holding the stirrups 36 and 37 in place may be used for securing said holder to the engine. Where the stud bolts provided with 20 the engine are of such a length that they do not reach through the slots 52 and 53 of the body reaches 46 and 47, I employ two nuts 60 and 61 which are constructed as clearly 25 shown in Figs. 1, 5 and 6. Each of these nuts is elongated in formation being threaded internally throughout its length. The same is turned down at one end to form a collar 63 and provide a shoulder 62 adjacent 30 the end thereof and is similarly turned down at its other end to form a sleeve 64 and provide a shoulder 65 leaving a portion 66 between said shoulders for engagement with a wrench. In use the sleeve portions 64 of 35 the nuts 60 and 61 are inserted through the openings 52 and 53 bringing the shoulders 65 in engagement with the body reaches 46 and 47. So arranged said sleeve portions project through these reaches sufficiently so that 40 the same may screw upon the ends of the manifold studs 33 and 34 to properly support the holder in clamping position. The relation of the various elements when these nuts are used in this manner is shown in detail in Fig. 6.

As before stated when the engine is equipped with sufficiently long stud bolts the nuts ordinarily furnished therewith may be used for holding the holder in place upon 50 said stud bolts. If desired the nuts 60 and 61 may be used instead for the same purpose. When so used said nuts are reversed and the collar portions 63 thereof inserted into the 55 openings 52 and 53 and screwed upon the ends of the stud bolts 33 and 34 with the shoulders 62 in engagement with the supporting members 46 and 47. In this manner the sleeve portions 64 of said nuts protrude outwardly beyond the supporting members 60 46 and 47, as clearly shown in Fig. 5. For carrying nuts 60 and 61 when not in use, I employ two threaded keeper studs 66 shown in Fig. 3, as being anchored on tie member 39, and upon which said nuts may be 65 screwed, as illustrated in Fig. 1.

The advantages of my invention are manifest. The device is extremely simple and may be manufactured at a nominal cost. The holder is readily adapted for use with several makes of internal combustion engines 70 being easily and quickly attached. Its use eliminates additional help in assembling the manifolds of a motor vehicle making it possible for one man, quickly and expeditiously, to perform the work ordinarily requiring 75 two men.

Changes in the specific form of my invention, as herein disclosed, may be made within the scope of what is claimed without departing from the spirit of my invention. 80

Having described my invention, what I claim as new and desire to protect by Letters Patent is:

1. A manifold holder for the intake and exhaust manifolds of an internal-combustion engine fitted with manifold studs, said holder including reaches apertured to receive said studs for attaching the holder to the engine in either of two positions, means formed on said reaches at one side thereof 85 for engagement with the intake manifold when said holder is attached to the engine in one of its positions, and means on the other side of said reaches for engagement with the exhaust manifold of said engine 90 when said holder is attached to the engine in its other position.

2. A manifold holder for the intake and exhaust manifolds of an internal-combustion engine fitted with manifold studs, said holder including reaches apertured to receive said studs for attaching the holder to said engine with either side thereof facing said manifolds, members issuing outwardly from said reaches at one side thereof adapted to 100 engage said exhaust manifold when said reaches are attached to the engine in one position, and an offset structure connecting said reaches and issuing outwardly therefrom for engagement with the intake manifold when said holder is attached to said engine in its other position.

3. A manifold holder comprising a reversible body portion, bearing means on one side of said body portion for engagement with the intake manifold of an internal-combustion engine, other bearing means on the other side of said body portion for engagement with the exhaust manifold of an internal-combustion engine, and means for 115 attaching said holder to an internal combustion engine for engagement with said manifolds in either position.

4. A manifold holder formed from bar iron comprising a base, offset portions issuing therefrom on one side thereof, oppositely extending body reaches issuing from said offset portions in parallelism with said base and legs issuing from the ends of said reaches extending therefrom in opposition 125 130

- 4 to said offset portions, said reaches having stud-receiving openings therethrough. 20
5. A holder for the intake and exhaust manifolds of an internal-combustion engine fitted with manifold studs, said holder comprising aligned, interconnected reaches, each reach being formed with an elongated opening therein to receive a manifold stud, bearing members for one manifold on one side of 10 said reaches, and bearing members for the other manifold on the opposite side of said reaches, said reaches being reversible on said studs to present said bearing members to their respective manifolds. 15
6. A holder for the intake and exhaust manifolds of an internal-combustion engine fitted with manifold studs, said holder comprising interconnected reaches, each formed with an opening therein, bearing members 20 for one manifold on one side of the reaches, and bearing members for the other manifold on the opposite side of said reaches, said reaches being reversible to present said bearing members to their respective manifolds, 25 holder clamping nuts for said studs, each nut having a sleeve-like portion adapted to be inserted through the opening in one of said reaches and fitted to one of said manifold studs, also having a shoulder to engage said reach at opposite sides of said opening. 30
7. A manifold holder for an internal-combustion engine having manifold studs, said holder comprising co-planer body reaches apertured to receive said studs, an offset tie and bearing structure, U-shaped in 35 form, joining said reaches, threaded keeper studs anchored to the base of said U-shaped structure between the legs thereof, clamping nuts for said manifold studs, said nuts being adapted to be threaded on said keeper studs, 40 at times of disuse, and thereby held protected within the confines of said U-shaped structure. 45
8. A manifold holder comprising a movable body portion, means on said portion for engagement with the intake manifold of an internal-combustion engine when said body portion is in one position, and other means on said body portion for engagement with the exhaust manifold of an internal-combustion engine when the body portion is in another position, and means for attaching said holder to an internal-combustion engine for engagement with either of said manifolds. 50
- 55

In testimony whereof, I have signed my name to this specification:

ENGBRIGHT A. WINDEN.
